(57) CLAIM

The ornamental design for a barbecue grill lid, as shown and described.

DESCRIPTION

FIG. 1 is an upper perspective view of a barbecue grill lid showing my new design.

FIG. 2 is a front elevation view thereof;

FIG. 3 is rear elevation view thereof;

FIG. 4 is a left side view thereof;

FIG. 5 is a right side view thereof;

FIG. 6 is a top plan view thereof;

FIG. 7 is a bottom plan view thereof; and,

FIG. 8 is an upper perspective view of the barbecue grill lid shown positioned on a barbecue grill.

The features presented in broken lines are for purposes of illustrating environmental structure that forms no part of the claimed design.
